PUMP

Lutwin C. Rotter, Maplewood, and Victor G. Klein, August D. Reisert, and Rudy F. Schneller, St. Louis, Mo., assignors to Lincoln Engineering Company, St. Louis, Mo., a corporation of Missouri

Application May 4, 1942, Serial No. 441,620

4 Claims. (Cl. 103—40)

This invention relates to pumps, and with regard to certain more specific features, to lubricant dispensing pumps.

The invention is an improvement upon the invention described in the United States Patent 2,276,207 of Victor G. Klein, dated March 10, 1942.

Among the several objects of the invention may be noted the provision of a lubricant pump which is driven by means of a continuously-operating, automatically-unloading internal-combustion engine, but which has a simplified pressure relieving apparatus, as compared to that shown in said patent; the provision of apparatus of the class described carried out in a compound form by means of a simple operating linkage for handling various supplies of lubricant; the provision of apparatus of the class described which operates very smoothly with optimum conditions of thrust; and the provision of apparatus of the class described which is knock-free and has minimum misalignment of parts or leakage under adverse conditions. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is an isometric view of the apparatus; Fig. 2 is a vertical, median section taken substantially along line 2—2 of said Fig. 1, parts being omitted but showing basic structural features;

Fig. 3 is a fragmentary horizontal section taken on line 3—3 of Fig. 2;

Fig. 4 is a horizontal section taken substantially along line 4—4 of Fig. 2;

Fig. 5 is a fragmentary horizontal section taken along line 5—5 of Fig. 1 and showing a pressure control device;

Fig. 6 is a view similar to Fig. 5 but showing a second and similar but high-pressure control device;

Fig. 7 is an enlarged fragmentary detail of a knock-eliminator, being taken on line 7—7 of Fig. 2;

Fig. 8 is a horizontal section taken on line 8—8 of Fig. 7;

Fig. 9 is an enlarged fragmentary detail of an

outlet check valve, being taken on line 9—9 of Fig. 2;

Fig. 10 is an enlarged fragmentary detail of a bleeder valve, being on line 10—10 of Fig. 2;

Fig. 11 is an enlarged detail of a labyrinth packing; and,

Fig. 12 is an enlarged detail of an eccentric strap.

Similar reference characters indicate corresponding parts throughout the several views of the drawings.

As stated in said Klein patent, in many cases it is desirable to operate a lubricant pump in locations where no electricity is available, and for this purpose a small internal-combustion engine, such as a gasoline engine or the like, is desirable. The desired lubricant flow, under pressure is irregular and intermittent, but it is not feasible to start and stop an internal-combustion engine accordingly. Furthermore, lubricant pressure should be instantly available at all times in the conduit which leads to the lubricant control valve for starting and stopping flow. The present invention accomplishes these ends by means of a construction improved over that of the patent.

Referring now more particularly to Fig. 1, there is shown at numeral 1 a chassis, including an axle 3 upon which are wheels 5, and also handles 7 for transport purposes. Vertical spacing pillars 9 on the chassis 1 support a small internal combustion engine 11 which constitutes the prime mover. This prime mover 11 is situated over an eccentric case 13 located substantially on a median line of the chassis 1. The eccentric case 13 has extension sleeves 15 and 17, at the front and back respectively. These cylinders 15 and 17 form enclosures and are capped by castings 19 and 21 respectively, held by tension studs such as 18 (Fig. 4). The assembly of parts 13, 15, 17, 19 and 21 is supported upon the chassis 1 by suitable pads, such as indicated for example at 2 in Fig. 1.

The forward casting 21 supports a lubricant container 23 located ahead of the prime mover 11, and the rearward casting 19 supports a lubricant container 25 located to the rear of the prime mover 11. By this arrangement there is obtained a very compact organization of parts for dispensing two grades of lubricant, for example gear lubricant from container 23, which requires only low pressure for dispensing, while in the container 25 is carried lubricant requiring higher pressure for dispensing.

The engine 11 has provision for cranking it from the side at a crown coupling 27. A fuel

supply tank is indicated at 29. A belt drive from the prime mover 11 to the case 13 is shown in general at 31. This drive is covered with a safety guard 4 (Fig. 1) and includes a belt 33 reaching from a pulley 6 on the engine to a pulley 35 (Fig. 3), the latter being keyed to a countershaft 37 borne in the eccentric case 13. The countershaft 37 carries a pinion 39 meshing with a gear 41 located upon a main pin 43, also borne in said eccentric case 13.

In order to prevent leakage from the case 13, the main pin 43 is enclosed at its ends by means of sealed caps 45, from which the pin 43 is separate. The countershaft 37 is sealed where it passes through the wall of the case 13 by means of a labyrinth packing indicated in general at 47 and detailed in Fig. 11. This labyrinth seal consists in a hat-shaped washer 49 which is held against a shoulder 51 by the hub 53 of the pulley 35. The hub 53 is held in place by nuts 55 and a key 57. The flange 59 of the hat washer 49 is located in a counterbore 61 of the case 13. To the left of the flange 59 is an overlapping circular gasket 63 which is held in place by means of an overlapping metal washer 65 fastened by holding screws 67.

The sealed space 61 is drained by means of a passage indicated at 66 in Fig. 3 so that any lubricant which runs along the bearing for the countershaft 37, and which cannot escape through the labyrinth packing 47 circulates back to the case 13 via passages 66.

Organized with the gear 41 by means of studs such as indicated at 69 is an eccentric 71, around which is an eccentric strap 73 having an extension 75 to the left (Figs. 2, 4 and 12). Into the strap is rigidly threaded at the left a connecting rod 77. At the right on the strap is an ear 79 carrying a pin joint 81 for a second connecting rod 83 reaching to the right. The center line A of the rigid threaded connection at 75 passes above a parallel line D passing through the eccentric center B. Center C is below the line D. Another way of stating the advantageous position of the center C is that it is located to one side of the line K, indicated in Fig. 2. This line K passes through the center of the universal joint at 87 and the eccentric center B. The side chosen is that corresponding to the side of the mechanism center line upon which the large-angled stroke is desired. For example, in Fig. 2, C is below K, and therefore the large-angled stroke of 83 occurs beneath the center line of the apparatus. This arrangement has effects later to be described.

The rigidly held connecting rod 77 is articulated to a relatively small plunger 85 by means of a universal joint 87. The pinned connecting rod 83 is articulated to a relatively large plunger 89 by means of a universal joint 91. The universal joints 87 and 91 are simple in mechanical form, each comprising a cross pin 93 rotary with a close fit in a clevis 95 on the respective connecting rod, and also a vertical pin 97 fixed in a clevis strap 99 on the respective plunger and upon which cross pin 93 is horizontally swinging with a close fit.

The fits between the pins 93 and straps 99 are loose and lateral misalignments are corrected for in the resulting available universal movement. By means of these simple universal joints, any misalignment introduced by the eccentrics (which are more difficult to maintain in alignment) does not throw unnecessary stresses upon the plungers 85 or 89. Although an eccentric is a simpler form of connection between the gear 41

and the connecting rods 77 and 83 in the present case, it is more difficult to align than its crank equivalent. In the present case the eccentric however is the preferable means for effecting the drive, since it can have the special compound connections with the connecting rods made more simply than if a double connection were to be employed with an ordinary crank.

Another feature of this drive is the fact that 10 the kinematic chain, constituted by parts 13, 71 (15, 77; the equivalent of one link), and plunger 85 constitute a so-called kinematically constrained four-bar chain. The linkage constituted by the parts 13, 71, 73, 83 and 89 constitutes a 15 five-bar chain which is ordinarily kinematically loose and not properly constrained; but in the present case, by reason of the coupling of this five-bar chain with the four-bar chain mentioned, through common links 13 and 71 the five-bar chain becomes kinematically constrained.

20 In view of the above, it will be seen that we have provided a novel compound driving linkage for two pumps, which linkage is very simple and strong.

25 Each plunger 85 or 89, as the case may be, operates in a cylinder, and since each of the cylinders is similar to the other and coaxial thereto but merely of different bore, only one will be described by way of example. This will be the cylinder in association with the plunger 85. Corresponding numerals on the other cylinder (in association with the plunger 89) indicate like parts.

30 Referring for example to the left-hand end or high-pressure end of the device (at the left of Figs. 2 and 4), numeral 101 indicates the body of the cylinder, which on the outside has a shoulder 103 abutting and sealed against the outside of the casting 19. This cylinder 101 is held in place by a nut 105 at its opposite end, which holds the cylinder in place across the inner pocket 8 formed by the casting 19. Crosswise of the cylinder 101 is an inlet port 107 which is counterbored to form a surrounding seat 109. The end of the plunger 85 reciprocates across the inlet port 107. It will be seen that the castings 19 and 21 constitute inlet manifolds for leading lubricant from the respective containers to the respective inlets 107.

35 Coaxial with the port 107 there is threaded into the casting 19 a holder 111 in which is a stem 113. The stem 113 passes through a packing head 115.

40 Inside, the stem 113 has a head 117 attached to which is a packing seat 119 for engaging the 55 seat 109 when the stem is forced inward.

45 At the other end, the stem 113 carries a shoulder piece 121 against which a spring 123 seats. This shoulder piece is normally pressed against a stop 10 by the spring 123. The spring reacts 60 at its other end against a threaded cup 125 which is adjustable in position by inserting a suitable wrench into an opening 127. The opening 127 may be reached through openings 129 in the body 111. By adjustably threading the cup 125, an 65 adjustment of the spring reaction may be obtained.

70 Seating in a recess in the head 121 is a small plunger 131 (in the case of the casting 19) and a larger plunger 133 (in the case of the casting 21). Packings 135 and 137 respectively are used to pack the plungers 131 and 133. Pressure connections 139 serve to connect inlets 141 respectively with the shouldered portions 103 of cylinders 101. These connections are made beyond

the outlet check valve (to be described) of the cylinders 101.

One of these check valves last mentioned is detailed in Fig. 9, and comprises a threaded bushing 143, having an opening 145 communicating with the respective cylinder 101 and normally covered by means of a plunger 147. The plunger 147 is biased to close the opening 145 by means of a spring 149. When the pressure on the end of the plunger 147 rises high enough, it is driven back to open the outlet to cross communicating side passages 151. This occurs upon each compression stroke of the respective plunger 85 or 89 as the case may be. Fluid then passes out of the openings 153 (Fig. 9) through an outlet bushing 157 (Figs. 2 and 4) and to a suitable hose 158 (in the case of the casting 21) and a hose 159 (in the case of the casting 19). Each hose carries a manual control valve 12.

A relief valve 161 directed downward is associated with each bushing 143. Fig. 10 details the relief valves, each of which comprises a bushing 163 having an inner opening 165 adapted to be closed by screwing down a hollow plug 167. When the plug 167 is backed off (as indicated in Fig. 10), its opening 169 is placed in communication with the opening 165 and pressure is therefore relieved. Normally these relief plugs are shut.

In the high-pressure container 25 is a follower 171 which rides upon the top of the grease supply in the container and with which is organized manually operable means for placing resilient pressure on the follower; but since this follower construction does not constitute a novel feature per se, and since it is specified in said Patent 2,276,207, it will not be described herein further.

Operation of the device, generally considered, is as follows:

The tanks 23 and 25 are respectively filled with suitable lubricants and covers 173 applied, the follower 171 being arranged in proper following position upon the surface of the lubricant in the container 25. The covers 173 are closed.

Next, the relief valves 161 are opened temporarily.

Then the gasoline engine 11 is started from the starting device 27, by means of a suitable crank, winding rope or the like. Thereafter the engine 11 operates continuously until it is cut off in the usual manner. This continuous operation is transmitted through the pulley 6, belt 33, pulley 35, gears 39, 41, through the mechanism in the crankcase 13 to reciprocate the coaxial plungers 85 and 89.

Since, under the above conditions it may be assumed that there is substantially no pressure in either hose 158 or 159, the springs 123 are free to push back the stems 113, and thus will hold the heads 117, 119 clear of the seats 109 (see Figs. 4, 5 and 6).

As soon as the engine has started lubricant is pumped from relief valves 161 and as soon as the engine is in satisfactory operation for continuous action under load, the relief valves 161 are closed. This causes pressure to build up in the hoses 158 and 159, it being understood that the hand valves 12 used respectively at the ends of these hoses are normally shut. The pressure, as it builds up, is transmitted through the communicating lines 139 to the respective plungers 131 and 133 so as to press the heads 117 along with their packings 119 against the seat 109. Thus closure of the inlets 107 occurs at predetermined pressures in the hoses 158 and 159, the

actual values of the pressures depending upon the adjustments of the springs 123 through the adjustments to cups 125. When the inlets 107 are closed, no more lubricant is available to be compressed against the charge already in the respective hose, and the engine therefore idles without being under load. The result is that fluid pressure is always instantly available in the hoses 158 as soon as the valves in the hoses open, but without the necessity of constantly operating the engine under load.

As soon as the outlet valve 12 of either hose 158 and/or 159 is opened, the respective pressure is incipiently reduced upon the respective plunger 131 or 133. Hence the respective spring 123 draws back the respective head 117 and thus opens the respective port 107 to provide lubricant for maintaining the respective hose pressure.

Whenever the outlet valve 12 from a hose 158 or 159 is closed, the pressure in the respective hose builds up, whereupon the pressure in the respective connection 139 builds up. For example, supposing that the pressure in the left-hand line 139 builds up, this will gradually push the corresponding plunger 133 so as to force its respective valve 117 against its seat 109, thereby closing off the supply of lubricant to the respective inlet 107. This unloads the plunger 85 and consequently unloads the engine 11 of this fraction of the load. Closure of the outlet of the other hose results in a similar action in respect to the other plunger 89. Thus it will be seen that opening either valve at the end of either hose 158 or 159 results in opening the inlet supply for the respective pump plunger, so that that plunger becomes operative to pump lubricant to the respective hose. But when a given valve is shut, then the plunger associated with its hose is relieved of the work of pumping lubricant, which occurs at a predetermined pressure in the hose.

The fact that point C (Fig. 12) is below line D makes the pressure thrust of the plunger 89 less angular than its suction thrust, with respect to the center lines of the respective cylinder 101. This is desirable since the axial force on the pressure thrust is greater, and by means of this low angularity, large side thrusts on the plunger 89 and associated cylinder are avoided.

Since the fluid which is being pumped is of the nature of a substantially incompressible fluid, though not completely incompressible, there is a tendency for a hammer or knock to occur due to surging, and this effect is eliminated in the present construction by threading to the compression end of each pump cylinder 101 a cup 175 which communicates by way of a passage 177. This cup has a removable enclosing and sealing cap 179 and contains loosely therein a cubicle or other mass of synthetic rubber 181 in which is an air bubble 183. This bubble may be blown into the rubber or, as shown in the drawings, the cubicle 181 may be made up of two parts which are vulcanized together along the line 185. When the rapidly rising pressure wave or surge from a compression stroke moves through the lubricant being pumped, it also reaches the contained cubicle of rubber and is transmitted compressively to the air bubble 183 therein. This acts as a buffer to prevent a hammer-like blow or knock, and in consequence the operation of the machine is smooth under the most rapid operation under heaviest pressures.

The advantage of the air bubble permanently enclosed by means of resilient material such as

synthetic rubber is that no complicated arrangement adjustment need ever be made in any part of the system to insure a trapped charge of air, as has been the case in systems where air compartments are used without such a device as herein described. It matters not whether there is air or lubricant in the chamber 115, so long as there is also therein the cubicle of rubber enclosing its bubble of air. It is preferable, however, that the chamber be filled with lubricant, because an excessive amount of air used as a cushion results in inefficient pumping action by the plungers 85 and 89. It will be understood that the volume of the air bubble 183 in the cubicle or rubber is predetermined and always the same and is as small as possible consistent with the elimination of knocking. Once the proper amount has been decided upon, no change in the operating characteristics occur. It should be understood that the cubicle of rubber may have any shape, such as cylindric or spherical, and that it may be made in one piece.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. Pumping apparatus comprising a cylinder, a reciprocating plunger in the cylinder, said cylinder having an outlet, and having an inlet crossed by the end of said plunger, a check valve in the outlet permitting only outward flow, a valve seat associated with said inlet, an inlet valve mounted for motion to and from said seat, a spring biasing said inlet valve away from the seat, a conduit leading from the outlet side of said check valve, a plunger exposed to pressure in the conduit and operative under a predetermined degree of said pressure to move the inlet valve against the seat and against the action of said spring, whereby at a predetermined outlet pressure flow of lubricant into the inlet is prevented and whereby further rise in outlet pressure from plunger operation is inhibited.

2. A lubricant pump comprising a cylinder, a reciprocating plunger therein, said cylinder having an outlet and having an inlet crossed by said plunger, a lubricant manifold around the inlet for leading lubricant thereto, a check valve in the outlet permitting outward flow only, a valve

seat associated with said inlet, an inlet valve assembly comprising a body attached to the manifold, packing means associated with said body, a stem passing through the packing means and 5 interiorly carrying an inlet valve opposite the inlet, a head on the other end of the stem, a spring pressing upon said head to bias the valve to open position with respect to the inlet, adjustable means reacted upon by the other end of the spring, said body having an opening for reaching said adjustable means for adjustment, a plunger associated with said stem, and a pressure connection between the outlet side of said check valve and said plunger, whereby a predetermined outlet pressure will effect automatic closure of said valve against bias of said spring.

3. Pumping apparatus comprising a cylinder, a reciprocating plunger in the cylinder, said cylinder having an outlet and an inlet, said plunger moving material from the inlet to the outlet, a check valve in the outlet permitting only outward flow, a valve seat associated with said inlet, an inlet valve mounted for motion to and from said seat, a spring biasing said inlet valve away 20 from the seat, a conduit leading from the outlet side of said check valve, a plunger exposed to pressure in the conduit and operative under a predetermined degree of said pressure to move the inlet valve against the seat and against the action of said spring, whereby at a predetermined outlet pressure movement of material into the inlet is prevented and whereby further rise in outlet pressure from pump operation is inhibited.

4. Pumping apparatus comprising a pressure pump having an inlet and an outlet, said pump transferring material from the inlet to the outlet and producing pressure, a check valve in the outlet permitting only outward flow, a valve seat associated with said inlet, an inlet valve mounted 25 for motion to and from said seat, means biasing said inlet valve away from the seat, a conduit leading from the outlet side of said check valve, a plunger exposed to pressure in the conduit and operative under a predetermined degree of said pressure to move the inlet valve against the seat and against the action of said biasing means, whereby at a predetermined outlet pressure movement of material into the inlet is prevented and whereby further rise in outlet pressure from pump operation is inhibited.
